UNITED STATES PATENT OFFICE.

JOEL T. CASE, OF BRISTOL, ASSIGNOR TO THE J. T. CASE ENGINE COMPANY,
OF NEW BRITAIN, CONNECTICUT.

STEAM OR WATER MOTOR.

SPECIFICATION forming part of Letters Patent No. 373,922, dated November 29, 1887.

Application filed August 10, 1887. Serial No. 246,561. (No model.)

To all whom it may concern:

Be it known that I, JOEL T. CASE, a citizen of the United States, residing at Bristol, in the county of Hartford and State of Connecticut, 5 have invented certain new and useful Improvements in Steam or Water Motors, of which the following is a specification.

My invention relates to improvements in steam or water motors, and the objects of my 10 improvements are to improve the construction and efficiency of the machine and to provide a construction which is applicable either to a steam-engine or a water-motor.

In the accompanying drawings, Figure 1 is a 15 vertical section of my engine, partly in elevation, the plane of section being indicated by the line $z z$ of Fig. 2. Fig. 2 is a vertical section thereof, partly in elevation, on line $x x$ of Fig. 1. Fig. 3 is a detail view showing 20 the steam-chest at one side of the case with its cap removed; and Fig. 4 is a horizontal section, partly in elevation, on line $y y$ of Fig. 2.

This invention is in the nature of an improvement upon the engine shown and described in my application No. 241,094, filed 25 June 13, 1887.

Although the construction herein described is adapted for either a steam or water motor, I shall for convenience describe its construction 30 as a steam-motor.

As in my aforesaid application, I prefer to make the case or frame A in the form of a shaft-hanger and provided with a cap, B, for covering one of its broad sides. The two broad 35 sides of its case or frame also serve as plates for closing two sides of the steam cylinder or box C, which cylinder is also fitted to and oscillates and reciprocates on the central rocking block or piston, D, substantially as in my 40 aforesaid application. Instead, however, of mounting the rocking block or piston upon a hollow axle through which steam passes, I mount it upon a solid axle or shaft, a, preferably made a little tapering to compensate for 45 wear, and provided with adjusting-nuts $b b$, by which it is secured to and adjusted within the box or frame A.

In order to somewhat enlarge that surface of the cylinder or steam-box which works 50 against the broad side of the case, I provide the same with flanges c.

In each broad side of the case A and on that surface which is traversed by the steam-cylinder or box C, I provide four ports, $d d$ and $e e$, their position being indicated by broken lines 55 wherever they are hidden from view by other parts. These ports open into small steam-chests $f f$ and $g g$ on the outside of the case proper, which chests are covered by the caps h . The chests $f f$, on opposite sides of the case, 60 are connected by a passage-way, k , so that a steam-pipe (indicated by broken lines at E) in one of the caps h , for supplying steam to one chamber f , will also supply steam to the opposite chamber through the passage k . In like 65 manner the chests $g g$ are connected by a passage, l , so that exhaust-steam may pass from both chests out through the discharge-pipe F.

In order to increase the bearing-surface between the rocking block or piston D and the 70 cylinder or steam-box mounted thereon, and also to elongate the ports $d d$ and $e e$, I provide the piston with flanges $m m$, and the ends of the cylinder or steam-box C with correspondingly-shaped recesses, as shown most clearly 75 in Fig. 1. In order that these flanges may not obstruct the ports, I make them a little shorter than the thickness of the case on its inside, so that, as shown in Fig. 3, they do not bear against the sides of the case. 80

The reciprocating and oscillating cylinder and steam-box C is connected by means of any suitable connecting-rod, n, Fig. 1, with the crank-pin o of the shaft G.

With the parts in the position represented 85 in Fig. 1, and with steam admitted at E into the steam-chests $f f$, the steam will pass in through the lower ports, d , thereby forcing the cylinder or steam-box C downward and driving the crank-pin o in the direction indicated 90 by the arrow in Fig. 1. At the same time exhaust-steam will be passing into the steam-chests $g g$ through the upper ports, e , and out through the exhaust-pipe F. As the crank and cylinder travel onward these ports are both 95 gradually closed until the crank-pin o is at the bottom of its motion and in the same vertical plane as the center of the axle a. At this point all of the ports will be closed; but so soon as the crank-pin passes this point steam will 100 pass in at the upper ports, d , and exhaust-steam out of the lower ports, e , thereby driving the

cylinder in the opposite direction until the crank pin *o* reaches its highest elevation and begins to descend to again open the lower ports, *d*, and upper ports, *e*, and so on repeatedly.

5 By this construction the ports can be enlarged to admit and discharge a great quantity of steam, thereby running the engine at a high speed and furnishing it with all the steam that is desired. I am also enabled to so arrange the ports that a very little movement of the crank-pin will carry the cylinder into position to reverse its movement. In other words, there is only a very small portion of the travel of the cylinder in which all the ports are closed.

15 While I have described the steam as admitted at *E* and the discharge of the exhaust steam at *F*, the direction of the steam may be reversed. The result of such a change, supposing the parts to be in the position shown in Fig. 1, would differ from that before described only by driving the crank-pin *o* in the opposite direction from that indicated by the arrow in said figure.

The same construction is applicable to water-motors; but inasmuch as water is non-compressible, the confronting edges of the ports

c and *d* would be carried inward a little—that is, toward each other—so that they would not be quite closed when the cylinder is in a vertical position.

35

I claim as my invention—

1. The combination of a central rocking block or piston, the open-sided cylinder or steam-box mounted thereon, and the frame or case covering the open sides of the cylinder and provided with outlet and inlet ports located within the path traversed by said cylinder, substantially as described, and for the purpose specified.

2. The combination of the rocking block or piston, the open-sided cylinder or steam-box mounted thereon, the case covering the open sides of said cylinder and provided with inlet and outlet ports, the steam-chests on opposite sides of the case and outside of said ports, and a connecting-passage for uniting said steam-chests, substantially as described, and for the purpose specified.
